(57) **CLAIM**

I claim the ornamental design for a vehicle shelf, as shown and described.

DESCRIPTION

FIG. 1 is line drawing of a top/front/left perspective view of a vehicle shelf of the present design;

FIG. 2 is a top/rear/left perspective view thereof;
FIG. 3 is a front elevational view thereof;
FIG. 4 is a rear elevational view thereof;
FIG. 5 is a right side elevational view thereof;
FIG. 6 is a left side elevational view thereof;
FIG. 7 is a top side elevational view thereof;
FIG. 8 is a bottom side elevational view thereof;
FIG. 9 is a line drawing of a top/front/left perspective view of a vehicle shelf of the present design;
FIG. 10 is a line drawing of a top/rear/left perspective view thereof;
FIG. 11 is a front elevational view thereof;
FIG. 12 is a rear elevational view thereof;
FIG. 13 is a right side elevational view thereof;
FIG. 14 is a left side elevational view thereof;
FIG. 15 is a top side elevational view thereof;
FIG. 16 is a bottom side elevational view thereof;
FIG. 17 is a line drawing of a top/front/left perspective view of a vehicle shelf of the present design;
FIG. 18 is a top/rear/left perspective view thereof;
FIG. 19 is a front elevational view thereof;
FIG. 20 is a rear elevational view thereof;
FIG. 21 is a right side elevational view thereof;
FIG. 22 is a left side elevational view thereof;
FIG. 23 is a top side elevational view thereof;
FIG. 24 is a bottom side elevational view thereof;
FIG. 25 is a line drawing of a top/front/left perspective view of a vehicle shelf of the present design;
FIG. 26 is a top/rear/left perspective view thereof;
FIG. 27 is a front elevational view thereof;
FIG. 28 is a rear elevational view thereof;
FIG. 29 is a right side elevational view thereof;
FIG. 30 is a left side elevational view thereof;
FIG. 31 is a top side elevational view thereof; and,
FIG. 32 is a bottom side elevational view thereof.
The broken lines showing portions of the Vehicle Shelf are for the purpose of illustrating environmental structure and form no part of the claimed design. The surface shading is not intended to indicate surface decoration of the vehicle shelf.
